UNITED STATES PATENT OFFICE.

THOMAS ELLIOTT, OF BIRMINGHAM, ALABAMA, ASSIGNOR TO CONTINENTAL GIN COMPANY, A CORPORATION OF DELAWARE.

BELT TIGHTENER.

Application filed September 20, 1926. Serial No. 136,483.

My invention relates to devices for regulating the tension imposed upon belts, bands, chains, and the like; and has particular reference to such devices which are intended to be used for regulating the tension of belts and similar endless members such as are commonly used for the transmission of power from one rotatable element to another.

A primary object of my present invention is to produce a device of the said general character, having means for adjusting the position or positions of a tension-regulating member or members, without the necessity of preliminary release of said member or members, or their support or supports, to permit of their being moved.

Another object is to provide for the retention of the tension-regulating member or members in selective positions, both by means adapted for moving said member or members to adjust the position or positions thereof, and by means effective independently of said moving means.

And a further object is to afford such tension-regulating means which are held in operative position partly by engagement of the belt or the like with a part of said means.

The means by which the foregoing and other objects are accomplished by my invention, and the manner of their accomplishment, readily will be understood from the following description, or reference to the accompanying drawings, which depict a preferred embodiment of the invention, and in which:

Fig. 1 is a side elevation of my improved belt-tightener, the pulleys thereof being offset, and parts only of the belt being shown.

Fig. 2 is a front elevation of the same, with the shell of the lower idler pulley partly broken away.

Fig. 3 is a side elevation of the supporting bracket of the belt-tightener, shown on a larger scale.

Fig. 4 is a side elevation of the slide in which the idler pulleys are mounted, shown on the same scale as Fig. 3.

Fig. 5 is a front elevation of the same.

Referring now to the drawings in detail, in which the various parts are indicated by the same reference characters in the different views, it will be seen that my improved belt-tightener comprises a supporting bracket 7, a slide 8 adapted to co-act therewith, and two similar idler pulleys 9 and 10,

all of said parts ordinarily being metal castings.

The bracket 7 comprises a body portion having parallel, substantially plane major faces 11 and 12; having an extended portion 13, lying in the same planes with said body portion, and terminating in a substantially plane surface 14 which is substantially at right angles to the longitudinal center line of said extended portion, and to the planes of the faces thereof; and having an offset portion 15 projecting substantially at right angles from the face 12 of said body portion, at the opposite end thereof from the extended portion 14. Said offset portion 15 has a lip 16 projecting from its outer face at the upper edge thereof, and has a bolt hole 17 therein at the approximate center of the offset, so that the bracket 7 may be secured firmly in place on a suitable support, by the use of a single bolt. A slot 18, having parallel sides, and substantially semi-circular closed ends, extends from near the upper end of the extended portion 13 of the bracket to a point near the lower side of the body portion thereof.

The slide 8 comprises a body portion of substantially the same thickness as the body portion of the bracket, and of such a width as to fit slidably in the slot 18, said slide terminating at its upper end in a right-angle offset 19, having a screw-threaded opening 20 therein adapted for the reception of a thumb-screw 21; and said slide having a bend at 22 and a reverse bend at 23, so that the lower end of the slide is parallel with its upper end, and is offset therefrom in the same direction as offset 19, to a distance approximately equal to the thickness of the bracket 7 at and near the slot 18. At approximately the middle of the bracket, it is provided with a boss 24, on the same side as the offset 19, the distance that said boss projects being such that its outer plane face lies in substantially the same plane with the outer face of the lower end of the slide, and said boss having a cylindrical opening 25 formed axially thereof and extending through the slide. At the respective sides of the lower end of the slide, it is provided with two similar ears 26, the respective plane faces of which lie in the same planes with those of said lower end, and said lower end is provided with a boss 27, similar to boss 24 but projecting in the opposite direction, 115

and having a cylindrical opening 28 formed axially thereof and extending through the slide, the outer plane face of said boss lying in substantially the same plane with the face 5 of the upper end of the slide which is at the same side thereof as said boss.

The two idler pulleys 9 and 10 are each provided with double ball bearings, and are similarly mounted upon the slide 8, pulley 9 10 being placed adjacent boss 24, and pulley 10 being in line with boss 27, but at the opposite side of the slide therefrom. Each of said pulleys has an annular flange 29 at its outer end, and has a cylindrical opening 15 30 extending axially through the pulley. Two similar ball bearings 31 are placed in said opening, at the respective ends of the pulley, being force-fitted or otherwise suitably secured in said opening. A cylindrical 20 stud 32, having a hexagonal head 33 at one end, and exteriorly screw threaded at the opposite end for the reception of a nut 34, has a cylindrical opening 35 formed axially thereof, said opening extending from 25 the threaded end of the stud nearly to its head end, and being interiorly screw-threaded at its open end to receive the threaded shank of a grease cup 36. Between the ball bearing at the non-flanged end of the pulley 30 and the adjacent portion of the slide 8 (which portion will be the plane end of boss 24 in the case of pulley 9, and the face of the lower end of the slide 8 in the case of pulley 10), is a washer 37, so that any 35 tendency of the inner ball-races of the ball bearings to turn relative to the stud 32, is opposed, due to said races being clamped tightly between the head of said stud and said washer, and at the same time the stud 40 is securely retained in a position at right angles to the face of the slide 8. An opening 38 leads radially from the opening 35 in stud 32 to the exterior of said stud, and provides for the passage of lubricant from 45 the grease cup 36 to the ball bearings.

As indicated in Fig. 1, the pull of the belt upon pulleys 9 and 10 tends to move the slide 8 downward, which movement is opposed by the thumb-screw 21 which has 50 threaded engagement with the offset portion 19 of the slide, with the lower end of the set screw in engagement with the plane surface 14 at the upper end of extension 13 of the bracket. Thus, downward movement of the 55 thumb-screw moves the slide 8, and hence pulleys 9 and 10, upward, and increases the tension of the belt, while upward movement of said screw permits the slide to be moved downward by the pull of the belt upon said pulleys, and the tension of the belt is reduced accordingly.

To assemble the bracket and the slide, with the two pulleys and the grease cups in place on the slide (the diameter of the grease 65 cups being less than the width of the open-

ing in the slot 18 in the bracket), the upper portion of the slide is passed through said slot from the side of the bracket at which the pulleys are to be located, and the slide is moved upward in said slot until the offset portion 19 of the slide, and the lower end of the thumb-screw, clear the surface 14 at the top of the bracket, the thumb-screw being retracted if necessary. The upper portion of the slide is then brought closely into engagement with the face of the extension 13 of the bracket, which brings the ears 26 into engagement with the face of the extension 13 of the bracket near the lower end thereof. The position of the slide, and hence 70 that of the pulleys 9 and 10, may now be regulated by suitable adjustment of the thumb-screw.

In the use of my improved belt-tightener, there are no screws, bolts or other parts that 75 must be loosened or otherwise manipulated in order to permit adjustment of the positions of the idler pulleys, and the pull of the belt holds the upper end of the slide, and the ears 26, tightly in engagement with the 80 bracket, and thereby keeps the faces of the pulleys 9 and 10 in the desired alinement relative to the faces of the other pulleys over which the belt runs. The tendency of the pull of the belt on the upper pulley 9 is 85 to hold the upper portion of the slide against the face of the extension 13 of the bracket, and that of the pull of the belt on the lower pulley 10 is to hold the ears 26 against the opposite face of the bracket, due 90 to the overhung arrangement of said pulleys.

Various modifications of minor details of my improved belt-tightener doubtless readily will suggest themselves to those skilled 105 in the art to which it appertains, but such modifications fall within the scope of my inventive rights, and my invention is not to be construed as being limited to any details not specifically set forth in the appended 110 claims.

Having thus described the invention, what I claim as new, and seek to secure by Letters Patent, is:—

1. A belt-tightener, comprising a bracket, 115 a slide carrying an idler pulley over which the belt passes and movable relative to said bracket substantially in the line of pull of said belt upon said pulley, opposed faces of said slide being slidably engaged with opposite sides of said bracket, both of said faces being held in such engagement by the pull of the belt upon said idler pulley, and means 120 for moving said slide counter to the pull of the belt to increase the tension thereof.

2. A belt-tightener, comprising the elements recited in claim 1, and having in addition thereto a second idler pulley carried by the slide and over which the belt passes, the pull of the belt on the two pulleys tend- 125

ing to retain both faces of the slide in slid-
able engagement with the bracket.

3. A belt-tightener, comprising a slotted
bracket, and a slide carrying two idler pul-
leys over which the belt passes and movable
in the slot in said bracket with opposed faces
of said slide engaging opposite sides of the
bracket, the pull of the belt upon said pul-
leys tending to retain said slide in slidable
engagement with both sides of said bracket,
whereby said pulleys are held in predeter-
mined alinement relative to other pulleys
over which the belt passes.

4. A belt-tightener, comprising a bracket;

a slide movable on said bracket and carrying 15
an idler pulley over which the belt passes,
said slide being free for adjustment sub-
stantially in the direction of the pull of
the belt upon said pulley, and having oppo-
sitely-facing portions adapted to engage op- 20
posite sides of the bracket, the pull of the
belt upon said pulley being adapted to hold
said slide portions positively against said
bracket; and means for moving said slide to
vary the tension on the belt. 25

In testimony whereof I affix my signature.

THOMAS ELLIOTT.
